US00D523153S

(12) **United States Design Patent** (10) **Patent No.:** **US D523,153 S**
(45) **Date of Patent:** **** Jun. 13, 2006**

(54) **MAIN PART FOR IMMUNITY ANALYSIS MACHINE**

(75) Inventors: **Takuya Akashi**, Musashino (JP); **Mitsuru Onuma**, Tokyo (JP); **Susumu Sakairi**, Hitachinaka (JP); **Shiho Tanaka**, Hitachinaka (JP); **Koichi Suzuki**, Hitachinaka (JP)

(73) Assignee: **Hitachi High-Technologies Corporation**, Tokyo (JP)

(**) Term: **14 Years**

(21) Appl. No.: **29/219,642**

(22) Filed: **Dec. 21, 2004**

(30) **Foreign Application Priority Data**

Jul. 23, 2004 (JP) 2004-022102

(51) **LOC (8) Cl.** **24-02**

(52) **U.S. Cl.** **D24/232; D10/81**

(58) **Field of Classification Search** D10/81; D24/232-234; 198/468.3, 468.11; 356/445, 356/448; 366/218; 422/56-58, 63-98, 100, 422/105, 55, 59-62; 424/94.61; 435/85.1, 435/28; 702/22

See application file for complete search history.

(57) **CLAIM**

We claim the ornamental design for a main part for immunity analysis machine, as shown.

DESCRIPTION

FIG. 1 is a front, top and right side perspective view of a main part for immunity analysis machine showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan elevational view thereof;

FIG. 7 is a bottom plan elevational view thereof;

FIG. 8 is a front, top and right side perspective view thereof with the covers opened; and,

FIG. 9 is a front, top and right side perspective view thereof in using condition with a monitor.

1 Claim, 6 Drawing Sheets

FIG. 1

*FIG. 2**FIG. 3**FIG. 4**FIG. 5**FIG. 6**FIG. 7**FIG. 8*

FIG. 9
